UNITED STATES PATENT OFFICE.

HAROLD JARVIS, OF TORONTO, ONTARIO, CANADA.

THERMOSTATIC CONTROLLER FOR GAS WATER-HEATERS.

1,172,459.

Specification of Letters Patent. Patented Feb. 22, 1916.

Application filed October 5, 1915. Serial No. 54,286.

To all whom it may concern:

Be it known that I, HAROLD JARVIS, a citizen of the United States of America, and resident of the city of Toronto, county of York, Province of Ontario, in the Dominion of Canada, have invented certain new and useful Improvements in Thermostatic Controllers for Gas Water-Heaters, as described in the following specification and illustrated in the accompanying drawings, that form part of the same.

The principal objects of the invention are, to effect a positive automatic control of the flow of gas to the burner of a gas water heater, thereby insuring the water contained within the storage tank being maintained at a uniform temperature.

A further object is to devise a form of thermostat control apparatus which is not subjected to constant fluctuation but cuts off the supply of gas sharply when the temperature rises to a predetermined point and also opens quickly, thereby obviating the dangerous conditions of back firing in the burner.

A still further object is to devise a control apparatus of simple and durable form which is not delicate in its parts and operation and therefore not liable to get out of order.

The principal feature of the invention consists in the novel construction and arrangement of parts, whereby the gas control valve is carried upon a lever operatively controlled by a thermostat bar, said lever having a break joint intermediate of its length and carrying an armature adapted to be affected by a permanent magnet for the closing of the valve.

In the drawings, Figure 1 is a plan view of my thermostat control apparatus showing the inclosing casing in section. Fig. 2 is a central longitudinal view in section. Fig. 3 is a diagrammatic view illustrating the arrangement of the thermostat heater and water reservoir.

Like numerals of reference indicate corresponding parts in each figure.

Referring to the drawings, 1 is the base of the thermostat casing formed with a hollow boss 2 arranged adjacent to one end and central of its width, the boss being connected by the pipe 3 to the water circulation pipe 4, the pipe 3 extending downwardly and being connected to the lower water circulation pipe 5 to the reservoir 6.

7 is a laterally arranged passage formed on the underside of the base 1 intermediate

of its length having an opening 8 leading upwardly through the base.

9 is a hollow boss formed at the end opposite to the boss 2 and threaded to receive 60 the gas pipe 10 which leads to the burner of the heater 11.

12 is a cap extending over the base 1 having a flange 13 extending outwardly and secured by screws 14 to the base 1. The gas 65 passage 7 is connected through the pipe 15 to a suitable gas supply and the gas flows into the hollow chamber 16 formed between the cap 12 and base 1 and finds egress through the gas pipe 10.

70 17 is a valve seat arranged in the opening to the gas pipe 10.

18 are a pair of upstanding lugs arranged on the base 1 adjacent to the end of the device containing the thermostat and spaced 75 each side of the longitudinal center.

19 is a lever pivotally supported upon a pin extending through the lugs 18 and having the end 20 extending to the rear of the pivot and engaging a compression spring 21 80 which is adapted to exert an upward pressure against the end 20 to cause a consequent downward movement of the other end of the lever.

22 is a copper tube fixedly secured in the 85 base 1 centrally of the boss 2 and extending downwardly within the pipe 3 having the lower end 23 thereof closed.

24 is a carbon stick arranged within the copper tube 22 and resting upon the closed 90 bottom thereof, the upper end having a metallic cap 25 extending above the inner portion of the boss 2.

26 is a set screw threaded in the lever 19 a short distance in front of the pivot and arranged directly over the center of the carbon stick 24, the lower end engaging the top of the metal cap, said screw being secured in an adjusted position by means of the lock nut 27. The forward end 28 of the lever 19 100 is formed jaw-shaped and pivotally supported between said jaws is a bar 30, one end of which extends over the top of the lever 19 and the other end extends forwardly beyond the pivot.

105 31 is a bolt adjustably secured in the rear end of the bar 30 and extending through the hole 32 in the lever 19.

33 is a spiral spring secured at its upper end to the bolt 31 and at its lower end to a 110 screw or other fastening member 34 secured in the base, said fastening member being

arranged in the bottom of a recess 35 in said base which allows sufficient room for the proper operation of said spring.

36 is a horseshoe magnet rigidly secured to the base 1 having the open ends arranged to extend each side of the gas outlet 10.

37 is a steel armature secured to the forward end of the bar 30 and adapted to engage the forward ends of the magnet upon the depression of the arm.

38 is a closed spring secured to the underside of the armature 37 and supporting a hemispherical valve 39 which is adapted to close down upon the valve seat 17 and to shut off the outward flow of gas.

In the operation of this device, the temperature of the water in the circulation pipes 4 and 5 acts directly upon the thermostat tube 22 and when the temperature of the water is low the said tube contracts and lifting upon the carbon stick contained therein, said stick presses upwardly against the set screw 26 and consequently tilts the lever 19 upon its pivot against the action of the spring 21. This lifts the bar 30 and consequently the valve 39 thus opening the flow of gas to the heater. In the opening of the valve the magnetic pull of the electromagnet upon the armature 37 holds the said armature so that the lever 19 moves a certain distance without disturbing or disconnecting the armature from the magnet. The bar 30 however swings upon its pivot in the jaw-shaped end of the lever and consequently the inner end of the said bar pulls away from the lever 19 against the tension of the spring 33. When the tension of the spring 33 is increased by the upward movement of the lever 19 to such an extent as to overcome the magnetic pull upon the armature, the said armature is immediately released and the spring 33 pulls the lever 30 downwardly with a quick snap, thus making the opening of the valve instantaneous. This allows the flow of gas to the burner of the water heater. As the water becomes heated the thermostat tube 22 gradually lengthens and allows the carbon stick to drop. The compression spring 21 pushing upwardly on the rear end of the lever 19 holds the screw 26 in contact with the upper end thereof and the spring 33 also pulling downwardly causes the valve 39 to move downwardly to close as the temperature of the water increases until the armature carrying the valve moves within the influence of the pull of the magnet, when the armature is attracted and closes the valve with a snap.

It will thus be seen that with this construction of device a very quick opening and closing of the supply of gas to the heater is obtained and the valve 39 being carried on a flexible support will always seat itself. Another and important feature in this invention is that the valve opens against the

pressure of gas and closes with it, consequently the maximum effectiveness of closure is procured. The quick opening of the gas passage is most essential as slow opening of the gas supply to a Bunsen burner will result in back firing and consequently the heater is rendered both inoperative and dangerous.

The device herein described is very simple of construction and may be manufactured very cheaply. It is also positive in its action and is not of a delicate nature and cannot readily get out of order.

It will be particularly noted that the thermostat operating device is shown and described as arranged in circulation pipes outside of the reservoir. This feature is important in that the small body of water passing through the circulating pipes is more readily susceptible to external atmospheric conditions and as the temperature of the water within the reservoir becomes lower the temperature within the circulating pipes will drop quicker and consequently start the automatic thermostat into operation before the temperature of the water in the reservoir gets to the lowest desired point, thus allowing sufficient time for the natural lag in the action of the snap opening and closing valve to operate.

What I claim as my invention is:—

1. In a thermostatic controller for gas water heaters, the combination with a gas supply and a heater, of a valve adapted to close the gas passage to the heater, a fixed magnet armature connected to said valve, a magnet adapted to attract said armature to hold the valve closed, a thermostat adapted to control the opening and closing of the valve, and a spring tension means interposed between the thermostat and the valve to effect the quick opening and closing of the valve.

2. In a thermostatic controller for gas water heaters, the combination with a gas supply and a heater, of a valve adapted to close the gas passage to the heater, a pivotal arm supporting said valve and having a break joint intermediate of its length, a fixed magnet, an armature carried on said arm adapted to coöperate with said magnet, a tension spring holding said break joint, and a thermostat adapted to operate said arm to open and close the valve.

3. In a thermostatic controller for gas water heaters, the combination with a gas supply and a heater, of a valve adapted to close the gas passage to the heater, a lever pivotally supported adjacent to one end, a thermostat controlled by the heater and engaging said lever to swing it upon its pivot, an arm pivotally mounted on said lever and having one end spring held in contact with said lever, a valve mounted on the outer end of said pivotal arm adapted to close the gas

- passage to the heater, a magnet armature secured to the outer end of said pivotal arm, and a fixed magnet arranged to coact with said armature to attract the same to close 5 the valve.
4. In a thermostatic controller for gas water heaters, the combination with a gas supply and a heater, of a valve chamber interposed in the gas supply, a valve seat arranged at the outlet from said valve chamber, a lever pivotally mounted within said valve chamber, an arm mounted intermediate of its length at one end of said lever, a valve at the outer end of said arm adapted to engage 10 said valve seat to prevent the outflow of gas to the heater, a thermostat adapted to engage said lever between the pivot and the outer end supporting the valve arm and adapted to raise and lower said arm to open 15 and close the gas passage, a magnet arranged adjacent to the outer end of the valve supporting arm, an armature carried on said arm adapted to coöperate with said magnet to hold the valve in its closed position, and a 20 tension spring secured in the valve chamber and adjustably connected to the end of the valve arm at the end opposite to the end carrying the valve.
5. In a thermostatic controller for gas water heaters, the combination with a gas supply and a heater, of a valve chamber interposed in the gas supply, a valve seat arranged at the outlet from said valve chamber, a lever pivotally mounted within said 25
- valve chamber, an arm mounted intermediate of its length on one end of said lever, a valve at the outer end of said arm adapted to engage said valve seat to prevent the outflow of gas to the heater, a carbon stick thermostat supported from said valve chamber and 30 extending therewithin and engaging the valve operating lever between the pivot and the valve, a spiral compression spring engaging an extension from the lever and holding said lever in constant engagement with 35 said thermostat, an adjustable contact means between said lever and said thermostat, a magnet armature carried by the valve supporting arm on its outer end, a magnet adapted to coact with said armature to hold 40 the valve to its seat, and a tension spring connected to the inner end of said valve supporting arm.
6. In a thermostatic controller for gas water heaters, the combination with a gas supply, water reservoir and heater, of a thermostat arranged within the water circulating pipes outside of the reservoir, a valve adapted to close the gas passage to the heater, spring tension means supporting said 45 valve and operatively engaging the thermostat, a magnet armature carried by said spring tension means supporting said valve, and a magnet adapted to coact with said armature to effect a snap closing and opening of the valve. 50 55 60 65

HAROLD JARVIS.
